SHOE AND METHOD OF MAKING THE SAME

Original Filed Oct. 8, 1927

UNITED STATES PATENT OFFICE

TYCHO BUEK, OF PHILADELPHIA, PENNSYLVANIA

SHOE AND METHOD OF MAKING THE SAME

Application filed October 8, 1927, Serial No. 224,840. Renewed December 15, 1930.

My invention relates to new and useful improvements in a shoe and the method of making the same and has for its primary object to first produce a pattern into which pieces 5 of leather or other material are to be woven to provide a design partially if not wholly, predetermined by the pattern.

Another object of the invention is to provide a method of weaving designs in the 10 vamp or other parts of a shoe by cutting out various pieces of the shoe parts and slitting, punching, or perforating said parts to create or make a pattern or design and interlacing strips of leather or other materials through 15 the slots, slits, apertures or perforations so as to give a woven effect of any desired design and color.

A further object of my invention is to produce a shoe a portion of which has a design 20 or designs woven therein, said design or designs being predetermined prior to being incorporated in the shoe.

A still further object of the invention is to produce a shoe vamp having a design woven 25 therein.

With these ends in view, this invention consists in the details of construction and combination of elements hereinafter set forth and then specifically designated by the claims.

30 In order that those skilled in the art to which this invention appertains may understand how to make and use the same, I will describe its construction in detail, referring by numerals to the accompanying drawings 35 forming a part of this application, in which:

Fig. 1 is a side elevation of a shoe constructed in accordance with my invention and illustrating one design.

Fig. 2 is an enlarged face view of one of 40 the blanks.

Fig. 3 is a reverse face view of a completed vamp showing another formation.

In carrying out my invention as herein embodied, I provide a blank 7 of proper 45 shape to form any part of a shoe upper, but for convenience of illustration, one part shown will be a shoe vamp. The blank is of any suitable material generally used for making shoe uppers and has apertures in the form 50 of slots, holes or perforations, or slits formed

therein and any of these by themselves or in combination of the several forms of apertures and slits may be used.

In Fig. 2, I have shown a plurality of spaced slots 8 of varying lengths with slits 9 55 in the material between the slots and between the edges of the blank and said slots, but of course it is to be understood that these may be differently arranged according to the design desired in the finished article. 60

Through the apertures or slots and slits, are interlaced or woven strips 14 of leather or other suitable material and said strips may all be of one color or of various colors and they may be of a shade similar to that of the 65 blank or other suitable contrasting color or colors.

Where the strips 14 are tightly interlaced due to the arrangement of the slits, it is unnecessary to further secure the strips 14 as 70 will be obvious, but where the interlacing or weaving is more open, it is necessary to fasten the ends of the strips which may be done by any suitable means as by cementing or stitching, the latter being illustrated and the 75 stitches being shown at 15, Fig. 3.

After the strips have been interlaced into the blank to form the vamp or other part of the upper, said part may be embodied in a shoe in the usual manner. 80

By constructing a shoe upper part in accordance with the invention above described, any design may be produced in said shoe upper part prior to incorporation in a shoe. 85

Of course I do not wish to be limited to the exact details of construction as herein shown, as these may be varied within the limits of the appended claims without departing from the spirit of my invention. 90

Having thus fully described my invention, what I claim as new and useful is:

1. The method of producing a shoe upper part which consists in providing a blank of the desired shape, then forming slots and also slits between adjacent slots parallel therewith to produce a predetermined pattern, and then weaving strips through the slots and slits to complete a design. 95

2. A shoe upper part comprising a piece of material of the shape desired, said piece of 100

material having a plurality of spaced parallel slots with slits in the material between said slots, said slits being relatively shorter than the slots, and strips of material interlaced through said slots and slits.

3. In a shoe, an upper having spaced parallel slots of varying lengths produced by cutting and removing sections of the material from the upper and further provided with slits in the material between adjacent slots and of relatively less length than contiguous slots, and strips interlaced through said slots and slits.

In testimony whereof, I have hereunto affixed my signature.

TYCHO BUEK.
